DESIGN FOR A PAPER NAPKIN

Soichi Nakashima, San Francisco, Calif.

Application November 1, 1937, Serial No. 72,548

Term of patent 3½ years

To all whom it may concern:

Be it known that I, Soichi Nakashima, a subject of the Emperor of Japan and a resident of the city and county of San Francisco, State of California, have invented a new, original, and ornamental Design for a Paper Napkin, of which the following is a specification, reference being had to the accompanying drawing, forming part thereof.

out, and Figure 2 is a folded over perspective view thereof.

The characteristic feature of the design resides in the circular napkin ornamented and folded as shown.

I claim:

The ornamental design for a paper napkin, substantially as shown and described.

SOICHI NAKASHIMA.
